UNITED STATES PATENT OFFICE.

JASPER BLACKBURN, OF CHILlicothe, MISSOURI.

ANCHOR FOR GUY-WIRES.

No. 812,003.

Specification of Letters Patent.

Patented Feb. 6, 1906.

Application filed May 24, 1905. Serial No. 261,984.

To all whom it may concern:

Be it known that I, JASPER BLACKBURN, a citizen of the United States, and a resident of Chillicothe, Missouri, have invented certain new and useful Improvements in Anchors for Guy-Wires, of which the following is a specification containing a full, clear, and exact description, reference being had to the accompanying drawings, forming a part hereof.

My invention relates to an anchor for guy-wires; and the object of my invention is to construct a simple inexpensive anchor for guy-wires and the like that is located in the ground and which will very firmly and thoroughly retain its position after once being located and which will require but very little manipulation while being placed in position.

My invention consists in a base-plate which carries and on which is arranged to slide a pair of plates and means whereby said plates are shifted outwardly from the base-plate when the device is anchored in the ground.

My invention further consists in certain novel features of construction and arrangement of parts that will be hereinafter more fully shown, described, and claimed.

Figure 1 is a sectional view through the ground in which my improved anchor is positioned and illustrating a wire-supporting post with its guy-wire attached to my improved anchor. Fig. 2 is a plan view of my improved anchor, the same being in a closed position in order to be inserted in the hole that is formed in the ground. Fig. 3 is a plan view of the anchor after the same has been opened or moved into its anchoring position at the bottom of the hole in which it is located. Fig. 4 is a longitudinal section taken on the line 4-4 of Fig. 3. Fig. 5 is a longitudinal section taken on the line 5-5 of Fig. 3. Fig. 6 illustrates the anchor at the bottom of the hole in which it is positioned and showing the manner in which the sliding plates are spread apart. Fig. 7 is a vertical section showing the preferred form of the device I make use of for spreading the plates of the anchor apart.

Referring by numerals to the accompanying drawings, 1 indicates the base-plate of my improved anchor, the same being preferably circular and of any size and material. Projecting upwardly from the center of this plate is a post 2, in the opposite sides of the lower portion of which is formed the horizon-

tally-arranged grooves 3. Formed through 55 this post above the grooves 3 is an aperture 4, in which is located the ends of a link 5, to which is fastened the lower end of the rod 6, that extends above the top of the ground and to which is secured the lower end of the guy-wire that is to be anchored.

Located on top of the plate 1 and adapted to slide thereon is a plate 7, which is preferably the same shape as is the plate 1, and formed in said plate 7 is a slot 8, that receives the post 2 and permits said plate 7 to slide upon the plate 1. The edges of the plate 7 adjacent this slot 8 travel in the lower portion of the grooves 3. Formed in the under side of the plate 7 on opposite sides of the slot 8 and parallel therewith is a pair of grooves 9, into which project pins 10, that are formed integral with the plate 1 and which pins form stops to limit the outward movement of the plate 7. These pins are so 75 located and the slots 9 are of such a length as that the plate 7 is stopped in its outward limit of movement when the edge of the plate is moved, so as to be in approximate alignment with the center of the post 2. 80

Formed integral with the top of the plate 7 and in alignment with the slot 8 is a series of upwardly-projecting lugs 11, by means of which the plate 7 is moved outwardly upon the plate 1 through the medium of a spreader 85 hereinafter described. Located on top of the plate 7 and adapted to slide thereon is a similar plate 12, provided with a slot 13, that performs the same functions as does the slot 8, the edges of said plate 12 adjacent the slot 90 13 traveling in the upper portions of the grooves 3. Formed in the under side of the plate 12 is a pair of grooves 14, that lie parallel with the slot 13 and in which grooves are positioned the upper ends of pins 15, formed 95 integral with the plate 1 and which pins form stops to limit the outward movement of the plate 12. The edge of the plate 7 directly opposite these pins 15 is cut away, as indicated by 16, in order that the plate 7 may be 100 moved over onto the plate 1, so that its edges coincide therewith. Formed integral with the top of the plate 12, in alignment with the slot 13 therein, is a series of lugs 16, that are for the purpose of receiving the end of the 105 spreader that is utilized for moving the plates 7 and 12 outwardly.

The form of spreader that I prefer to use

and which is shown in Figs. 6 and 7 comprises a block 17, provided with a vertical slot 18 and which is adapted to be removably positioned upon the upper end of the post 2.

- 5 Adapted to move outwardly and downwardly through the slot 18 is a bearing-block 19, that is connected by ball-and-socket joint 20 to the lower end of a screw-rod 21, that passes through the upper end of the 10 block 17. This bearing-block 19 carries a pair of outwardly and downwardly projecting pawls 22, the lower ends of which are adapted to engage behind the lugs 11 and 16. The upper end of the screw-rod 21 is secured 15 to the lower end of a suitable operating-handle 23.

To locate my improved anchor, a hole A is formed in the ground in direct alinement with the guy-wire that it is desired to anchor, 20 and after said hole is formed to the proper depth the anchor comprising the plates 1, 7, and 12, which are arranged one on top of the other, as seen in Fig. 2, are inserted in said hole and positioned at the lower end thereof.

- 25 The spreader, such as seen in Figs. 6 and 7, is now positioned upon the upper end of the post 2, and the lower ends of the pawls 22 are engaged behind the pair of lugs 11 and 16 nearest the outer edges of the plates 7 and 12. 30 The handle 23 of said spreader is now manipulated so that the screw-rod 21 is caused to travel through the upper end of the block 17, and as the bearing-block 19 moves downwardly the points of the pawls 22 are moved 35 outwardly, and as a result the plates 7 and 12 are correspondingly moved outwardly into the earth on opposite sides of the lower end of the hole.

If desired, the outer edges of the plates 7 40 and 12 may be sharpened or formed with knife-edges, although this is not absolutely necessary when said plates are comparatively thin.

- 45 When the plates 7 and 12 have been moved outwardly until the points of the pawls 22 disengage themselves from the lugs 11 and 16, the operation of the handle 23 is reversed to elevate the bearing-block 19, and consequently withdraw the points of the pawls 22 50 until said points engage behind the next succeeding pair of lugs 11 and 16. The spreading action is then repeated until the plates 7 and 12 are moved to their outward limits of movement or until the pins 10 and 15 occupy 55 the ends of the grooves 9 and 14. Thus the outer halves of the plates 7 and 12 occupy positions in the undisturbed earth on opposite sides of a hole A, and thus a broad bearing-surface is formed at the lower end of the hole. 60 The spreading device is now detached from the post 2, and the rod 6 is now swung into position so that it lies in alinement with the post 2, after which earth is tamped into the hole A around said rod and on top of the 65 plates at the bottom of said hole. Thus the

anchor is very securely located, and the lower end of the guy-wire, such as B, is secured in any suitable manner to the loop formed on the upper end of the rod 6.

The plates 1, 7, and 12 may be made in any size and of any thickness, and they may be also made in various shapes, such as oblong or triangular, it only being necessary that the two upper plates be arranged to slide upon the lower plate and to be provided with means whereby their movement is limited, and they must necessarily be provided with lugs or notches to receive the ends of a suitable spreading device.

A device of my improved construction provides a very effective anchor, inasmuch as the outer portions of the two upper plates extend into the undisturbed earth on each side of the hole, and the entire surface of the three plates bearing against the earth creates great 85 resistance to any pull upon the anchor when properly positioned.

The anchor is composed of a minimum number of parts, is easily manipulated, and possesses superior advantages in point of simplicity, durability, and general efficiency.

I claim—

1. In an anchor for guy-wires, a base-plate and a pair of plates equal in diameter to the base-plate and adapted to slide in opposite 95 directions on said base-plate, substantially as specified.

2. In an anchor for guy-wires, a base-plate, a post integral with and extending upwardly therefrom, and a plurality of plates equal in 100 diameter to the base-plate and adapted to slide in opposite directions away from the post; substantially as specified.

3. In an anchor for guy-wires, a base-plate, a post projecting upwardly from said base-plate, and a plurality of plates equal in diameter to the base-plate and arranged to be shifted laterally relative the base-plate and post; substantially as specified.

4. In an anchor for guy-wires, a base-plate, 110 a post integral therewith and projecting upwardly therefrom, and a pair of plates equal in diameter to the base-plate and adapted to be shifted in opposite directions relative one another, and there being slots formed in said 115 shifting plates through which slots passes the post carried by the base-plate; substantially as specified.

5. An anchor for guy-wires, constructed with a base-plate, a pair of plates arranged to slide upon said base-plate, there being grooves formed in the under sides of the sliding plates, and pins projecting upwardly from the base-plate into the grooves in the sliding plates; substantially as specified.

6. An anchor for guy-wires, constructed with a base-plate, a plurality of plates arranged to slide laterally upon said base-plate, a post integral with the base-plate, there being slots formed in the sliding plates through 130

which the post projects, there being grooves formed in the under sides of the sliding plates, pins projecting upwardly from the base-plate into the grooves, and lugs formed integral with the tops of the sliding plates to be engaged by suitable separating devices; substantially as specified.

In testimony whereof I have signed my name to this specification in presence of two subscribing witnesses.

JASPER BLACKBURN.
